UNITED STATES PATENT OFFICE.

ROBERT McCLENATHEN, OF AKRON, OHIO, ASSIGNOR, BY MESNE ASSIGNMENTS, TO INTERNATIONAL HARVESTER CORPORATION, A CORPORATION OF NEW JERSEY.

IGNITION SYSTEM.

1,221,200.

Specification of Letters Patent.

Patented Apr. 3, 1917.

Application filed February 20, 1913. Serial No. 749,634.

To all whom it may concern:

Be it known that I, ROBERT McCLENATHEN, a citizen of the United States, residing at Akron, in the county of Summit and State of Ohio, have invented certain new and useful Improvements in Ignition Systems, of which the following is a full, clear, and exact specification.

This invention relates to ignition systems, and more particularly to control means used in connection with such systems.

In a co-pending application on my triple ignition system, executed Feb. 1, 1913, I disclosed an ignition system in which the necessary spark for ignition purposes can be produced in three different ways, viz. by current from a battery passing through a timer, vibrator and coil; second, by passing current from the same battery through a different timer associated with a magneto, thence to the same coil; and third, by passing current generated in the magneto through the timer associated with said magneto to the same coil. If, for any reason, the timer not associated with the magneto should get out of order, the battery current, if a battery were used, could be passed through the timer associated with the magneto, or the magneto current pass through the timer associated with the magneto and supplied to the spark producing coil. If the battery should get out of order or, for any other reason, it is desired to discontinue the use of a battery, current could be supplied from the magneto through the magneto timer to the coil. Again, if the magneto should become defective, current from the battery through the timer, not associated with the magneto, could be supplied to the spark producing coil. This system is claimed in my co-pending application.

It has been found that when battery current is supplied through the timer associated with the magneto to the spark producing coil, the battery wears out in a comparatively short time for the reason that the duration of engagement of the contacts of the magneto timer is comparatively long when considered with respect to the duration of the repeated contacts of the vibrator connected in circuit with the timer not associated with the magneto. For this reason, the battery current is not supplied to the coil through the magneto timer except in cases of emergency. Again, it has been found

that when the battery current is supplied to the coil through the magneto timer instead of through the timer not associated with the magneto, the platinum contacts of the magneto timer are burned or destroyed more readily, due largely to the fact that the condenser which is connected across the contacts of the magneto timer is particularly adapted for use with current supplied from the magneto. The magneto when running slow produces a low output in current and voltage, and while operating at high speed leaves the platinum points in contact so short a time that the current does not have time to build up to an excessive value which would injure the platinum points. With the use of the battery current through the magneto timer, the current reaches a much higher value, especially on low magneto speeds, than is produced by the magneto at any time, and consequently, destroys the platinum points. It has been found by experience that engine operators, whether operating a stationary engine or an engine in an auto-vehicle, often turn the control switch to a position where battery current is supplied to the coil through a magneto timer, negligently or carelessly leaving the switch in such position thereby wearing out their battery in a shorter time than is necessary and at the same time rendering the life of the platinum contacts of the magneto timer shorter than should be the case, when the necessary spark could be produced more efficiently by other switch connections.

It is therefore the object of my invention to increase the efficiency of my triple ignition system, to render the system fool-proof, and to overcome carelessness and negligence on the part of the operator using the ignition system.

This object is accomplished by providing and properly locating a spring-pressed member which normally lies in the path of the operating key or handle of the master switch which controls connections of my ignition system. This spring-pressed member is so located that the switch cannot be thrown into a position whereby battery current is supplied to the spark producing coil through the magneto timer unless said member is first moved in a manner to permit said handle to pass the same to move the switch into the desired position.

The invention is illustrated on the accom-

panying sheets of drawings in which Figure 1 is a diagram showing a master switch and connections in my triple ignition system;

Fig. 2 is a front elevation of the switch 5 box, the switch handle or key engaging the spring-pressed stop member;

Fig. 3 is a sectional view through said switch box showing, among other things, the arrangement of the spring-pressed stop 10 member; and,

Fig. 4 is a side elevation of the switch handle or key.

The various novel features of my invention will be apparent from the description 15 and drawings and will be particularly set forth in the appended claims.

Referring first to Fig. 1, which discloses diagrammatically my selective triple ignition system, a battery 10 is adapted to furnish current through a switch 11 to the primary coil or coils 12 of a translating device 29 having a secondary or high voltage coil 13 from which the spark is produced, the current also passing through an independent timer 14 in one position of the switch 11. In another position of the switch

11, current from the battery 10 passes through said switch, translating or spark producing coils 12 and 13, and through a 30 timing device 15 which forms a part of a magneto 16 having an armature 16^a. In still another position of the switch, current is supplied from said magneto 16 through said switch 11, coil 12 and the timer 15 which is 35 associated with said magneto. The complete circuits will be more closely followed later.

As already stated, current from the battery is only to be supplied through the timer 15 associated with the magneto in cases of 40 emergency for the reasons given. It is, therefore, decidedly advantageous to prevent the careless throwing of the switch into the position which is to be used only in cases of emergency. To prevent the operator 45 from throwing the switch into the position in which battery current is supplied to the translating device or spark-producing coil through the timer 15 associated with the magneto, I have provided a spring-pressed 50 member 17 located in a switch cover 18, the spring-pressed positive stop member 17 lying in the path of a key or handle 19 which is adapted to operate the movable contacts 20, 21, and 22 of the master switch 11, said 55 contact being preferably mounted in a disk 23 of insulating material. Under normal operating conditions the spring-pressed positive stop member 17 projects out of the cover 18 to the extent that it lies in the path 60 of the switch key 19 so that the switch can be turned only into positions marked "Mag.", "Off" and "B-T," as shown in Fig. 2, the position of the key 19 when pointing to B-T, corresponding to a switch position 65 in which the battery current passes through

the spark producing coil and timer 14, which is independent of the magneto, and Mag. position corresponding to a switch position in which current from the magneto passes through the same spark producing coil and the timer 15 associated with the magneto. 70

When the switch key 19 points to the position B-T, which is the usual starting position, the master switch 11 is in a position permitting current to flow from battery 10 through conductor 24, terminal 25, stationary contact 26, movable contact 21, stationary contact 27, conductor 28, primary or low voltage coil 12 of the translating device 29, stationary contact 30, movable contact 20, stationary contact 31, vibrator 32, conductor 33, terminal 34, conductor 35, timing member 14, to ground and back to the battery 10. When this circuit is completed, current passes through the low voltage coil 12 and 85 at the instant that said circuit is broken at the contacts of the timer 14 a high voltage current is induced in the secondary coil 13 of the translating device 29, and with the help of the vibrator 32 a shower of sparks is produced at the spark plugs 36.

When the switch key 19 is in a position pointing to Mag., the master switch 11 is in a position in which current from the magneto coil 16 passes through conductor 40, 90 terminal 41, switch contacts 42, 21, 27, conductor 28, coil 12, switch contacts 30, 20, and 36, terminal 37, conductor 38, timing device 15, to ground and back to the magneto coil 16, the necessary spark being produced at 95 the spark plugs 36, in this case, when the circuit is completed through timer 15 associated with the magneto.

As stated above, the operator may move the switch into three positions, off, B-T 100 and Mag. freely. But when moving the switch in one direction from off position, he can move the switch no farther than the Mag. position for the reason that the switch key 19 passes into engagement with the spring-pressed positive stop member 17. If, in case 105 of emergency, as above considered, the operator desires to move the switch 11 into the position in which current can pass from the battery 10 through the timer 15 of the magneto, he must first remove or press the spring-pressed stop member 17 out of the path of the switch key 19 to permit said master switch 11 to be moved into such position indicated by B. M. on the switch box 110 18. With the switch in this position, current passes from battery 10 through conductor 24, terminal 25, switch contacts 26, 21, 27, conductor 28, primary coil 12, switch contact 30, 20, 36, terminal 37, conductor 115 38, through timer 15 to ground and back to battery 10, the necessary spark being produced at the spark plugs 36 as above considered. The switch is not left in this position longer than absolutely necessary, for 120 13

the reason that the battery will wear out in a comparatively short time and the platinum contact members of the timer 15, associated with the magneto, will be worn out much 5 more rapidly than if the switch were in another position.

When the master switch 11 is in the position corresponding to the position B—T of the switch key 19, the movable contact 22 10 of the switch 11 is in engagement with a stationary contact 45 so that a circuit may be completed from battery 10 through conductor 24, terminal 25, switch contacts 26, 21, 27, conductor 28, coil 12, stationary contact 30, button switch 46, contacts 22 and 45, terminal 47, conductor 48, to ground and back to the battery, when the circuit is closed at the button switch 46 for producing a spark for starting an engine without first 20 cranking the engine. Condensers 48^a, 49, and 50 are respectively connected across the contacts of timer 15, timer 14 and vibrator 32, for protective purposes.

It is evident that other means may be provided for preventing the switch from being moved into the emergency position, except when it is particularly desired so to do, instead of using the spring-pressed positive stop member 17 and that other arrangements and modifications may be used, and it is my intention to cover all such arrangements and modifications which do not involve a departure from the spirit and scope 30 of my invention as set forth in the appended 35 claims.

What I claim as new is:

1. In an ignition system, the combination of a source of current supply, a coil adapted to receive current therefrom, a plurality of 10 timing devices, through one of which current always passes when supplied to said coil under normal operating conditions, and means adapted normally to prevent the passage of current to said coil through a certain one of said timing devices.

2. In an ignition system, the combination of a battery, a magneto, two timing members, a coil for spark purposes, means for controlling the production of a spark through

the agency of said coil with said battery and 50 one timing member, or with the same battery and the other timing member, or with said magneto and the second timing member, and positive means adapted normally to prevent the production of a spark through 55 the agency of said battery and a certain one of said timing members.

3. In an ignition system, the combination of a battery, a magneto, a plurality of timing members, a coil for spark purposes, 60 means for controlling the production of a spark through the agency of said coil with said battery and one of said timing members, or with the same battery and another of said timing members, or with said magneto and one of said timing members, and means adapted normally to prevent the production 65 of a spark through the agency of said battery and a certain one of said timing members.

4. In an ignition system, the combination of a plurality of sources of current supply, a plurality of timing members, a coil for spark purposes, means for controlling the production of a spark through the agency 75 of said coil with one of said sources and one of said timing members, or with the same source and another of said timing members, or with another of said sources and one of said timing members, and means 80 adapted normally to prevent the production of a spark through the agency of one of said sources and a certain one of said timing members.

5. In an ignition system, the combination 85 of a source of current supply, a coil adapted to receive current therefrom, a plurality of timing devices through which current supply of said coil may be effected, and positive means adapted normally to prevent the passage 90 of current to said coil through a certain one of said timing devices.

In testimony whereof I affix my signature, in the presence of two witnesses.

ROBERT McCLENATHEN.
